UNITED STATES PATENT OFFICE.

MANUEL D. DOMINGUEZ, OF NEW ORLEANS, LOUISIANA, ASSIGNOR OF ONE-HALF TO CHARLES A. DENIS AND ONE-HALF TO GEORGE SARPY, BOTH OF NEW ORLEANS, LOUISIANA.

ELECTRIC FURNACE.

Application filed May 12, 1924. Serial No. 712,781.

To all whom it may concern:

Be it known that I, MANUEL D. DOMINGUEZ, a citizen of Spain, and resident of New Orleans, in the parish of Orleans and State of Louisiana, have invented certain new and useful Improvements in Electric Furnaces, of which the following is a specification.

My invention relates to electric furnaces of a type adapted for heating rivets, soldering-coppers, and other articles or objects, for melting metals which melt at moderate temperatures, and for other purposes.

An important object of the invention is to provide in a unitary appliance one or any reasonable plurality of heating compartments or receptacles, which may, if desired, be of different sizes or shapes, each receptacle having its own resistance heating element, and each receptacle preferably also having its own controlling element, such as a switch, together with suitable circuits and suitable provision for electrical and heat-insulation. By the provision of individual controlling switches any one or more of the heating receptacles or compartments can be operated at a time, and the consumption of current is therefore only that required for the particular work in hand.

Another object is to provide a convenient and improved arrangement of the parts or subordinate combinations of an electric furnace, and especially to provide a box or compartment containing the heating compartments or receptacles, with suitable heat- and electric-insulation and suitable circuit connections, and in combination therewith, suitable compartments conveniently arranged for heating-element terminal connections and for switch and main conductor connections, with suitable bus bars and wiring in each of said compartments; and further to arrange or support the complete appliance in a convenient position for use and manipulation of the controlling elements, this being preferably a position in which the walls of the box or casing (which is usually in the form of a rectangular prism) are inclined and not vertical or horizontal.

Another object is to provide conveniently manipulated ejectors for use when certain

objects, including rivets, rods, etc., are being heated.

The invention consists in structures and arrangement of parts realizing the above stated and other objects. The accompanying drawings sufficiently illustrate certain exemplifying embodiments of the invention. After considering these embodiments, skilled persons will understand that many variations may be made within the principles of the invention, and I contemplate the employment of any structures that are properly within the scope of the appended claims:

Fig. 1 is an end elevation of the invention in one specific embodiment.

Fig. 2 is a front elevation of the same.

Fig. 3 is a vertical section.

Fig. 4 is a plan view of one of the terminal or conductor boxes with the cover removed.

Fig. 5 is a plan view of the other terminal or conductor with the cover removed.

Fig. 6 is a face or plan view of the side of the furnace on which the switches are located.

Fig. 7 is a fragmentary detail, in enlarged section, of a somewhat modified structure or arrangement of parts.

Fig. 8 is a wiring diagram.

Fig. 9 is a detail view, in side elevation, of one particular form of conductor or bus bar.

While novel features of the invention may be embodied in a device or appliance that has only a single heating chamber or compartment, it is evident that for a great many purposes, such as heating rivets, it is necessary to heat a plurality of the articles at a time, and the number which must be heated at one time depends on the rapidity with which riveting operations are performed; it is, therefore, usually desirable to provide a plurality, and usually a very considerable number, of heating chambers or compartments in one substantially unitary or self-contained appliance.

For this purpose, therefore, a housing or box B is provided, usually of rectangular outline. While the detail construction of this housing may, of course, vary considerably, in one suitable form as here shown, it consists of outer or side plates 1, 2 and 3, which may be of any suitable material, such

as sheet iron or steel, of substantial thickness. While in some cases all of the side plates may be separate, in other cases it is convenient to form some of them as parts of a continuous sheet. For example, plates 1 and 2 may be portions of a continuous or integral sheet, and this sheet may also have a wall portion 4 bent at a right angle to the portion 2, and parallel to the portion 1, 10 forming one of three metal walls of a heater housing or compartment H. The fourth side of this inner compartment is closed by a wall 5 which is desirably composed of a sheet of asbestos or asbestos composition, or else by 15 a plurality of parallel strips of such material, the ends of this sheet or of the separate strips being secured to angle bars 6.

The walls or wall portions 1, 2, 3 and 4 are suitably braced or reinforced or secured 20 together by angle bars 7, 8, 9 and 10.

The partition consisting of the sheet or strips 5, spaces or separates from the heating casing H a relatively shallow box or compartment W which may be conveniently 25 identified as a heating-coil-terminal compartment.

At an upwardly presented side of the main housing or box B another relatively shallow chamber or compartment X is provided. This may be conveniently identified 30 as a wiring or switch-terminal compartment. This consists of side and end strips 12, 13 and 14 of suitable material, which desirably is material having insulating and heat-resisting qualities, such as asbestos or asbestos composition, or a suitable substitute therefor. The longitudinal strips 12 and 13 are placed 35 over thinner strips or sheets 16 and 17 which may be of similar material, and the strips 40 12 and 16, and 13 and 17 respectively, are secured to angle bars 8 and 9 by screws 18.

A cover plate 20 is provided, which usually 45 is of asbestos or asbestos composition or similar material, and is secured by screws 21 to strips 12 and 13. The end enclosure of the main housing B consists of sheet metal end plates 24.

While it is not necessary in all cases, for 50 reasons which will appear from the following description, it is preferable in many instances to support the main housing in an inclined or angular position as shown in Figs. 1, 2 and 3. For this purpose end supports or brackets 26 of strip metal are provided, these being substantially triangular 55 and being dimensioned to support the furnace in the position shown without danger of overturning.

One of the upwardly-inclined faces of the 60 heating chamber H has a thick liner 30 of asbestos or asbestos composition or similar material. Plate 2 and the liner are provided with registering apertures 31, which desirably have an outward taper or flare, and are 65 designed to give access to the individual

heating chambers or compartments. Each of these chambers consists of a tube 32 of suitable metal, preferably copper. These tubes may be variously dimensioned and shaped for various purposes. They may also 70 have different cross-sectional shapes, depending on the purpose for which they are to be used. The present structure, chosen as an example, is especially designed for heating rivets or soldering coppers, and it is therefore sufficient to show the heating tubes with 75 round cross-section. It is desirable to provide in one appliance, tubes or heating chambers of different sizes, as clearly indicated in Figs. 3 and 2, the last named figure showing 80 apertures 31 of different diameters, to correspond with the different diameters of the heating tubes. This provides for heating rivets or similar objects of different diameters. When designed for heating rivets, 85 each tube, desirably, has an upper end portion 33 of enlarged diameter, and the aperture 31 corresponds to the diameter of this enlargement. The enlargement 33 permits the formation of an annular shoulder 34 90 upon which the head 35 of a rivet rests while its shank or stem 36 fits closely within the main bore of the tube 32, to provide for the ready transfer of heat from the tube to the rivet. 95

The base of each tube 32 rests on a metal plate 40, and the upper end of each tube is formed with flanges or ears 41 which are secured to the liner 30 by screws 42 and nuts 43, the plate 2 having apertures 43 to give 100 access to the screw heads. Wherever necessary or desirable, for the mechanical or electrical connections, suitable lock washers are placed under nuts; for instance, nuts 43 may be secured by lock washers 44. Such locking 105 devices will not be further mentioned.

The base plates 40 have lateral extensions 46 which are apertured to accommodate screws 47, which are insulated from the plates 40 by bushings 48 of suitable insulating material. The screws serve to support and properly locate the base plates 40, and also serve as binding posts and conductors, as presently appears. The base plates are properly spaced from partition 5 by nuts 49, upon which the bushings 48 rest, and the bushings and base plates 40 are locked in position by nuts 50. 110

Surrounding each heating tube is a layer 120 of suitable insulating material 55, such as asbestos or asbestos "paper", and at the upper end of this tube is an integral or separate flange or washer 56 of similar material underlying the bottom face of the tube shoulder 34. 115

A suitable heating element is located around the insulation 55 and is by it insulated from the heating tube, although the heating element is in very close proximity to the tube. In a preferred example, as here 130

shown, it consists of a double coil or helix 60 of suitable wire, such as "nichrome" wire, wound about the insulating tube 55 in the manner shown. The two portions of the 5 helix are connected at their upper end by a loop or bend 61, which is properly secured or located by a pin 62, which is usually insulated; or in some cases definite retention of the upper end of the double helix is un- 10 necessary. The end of one portion or strand of the heating wire is suitably looped and passed about one of the adjacent binding screws 47 and secured by a nut 64, and the end of the other portion of the helix is 15 looped and passed over the other adjacent binding screw 47 corresponding to the particular heating tube, and secured by a similar nut 64. An insulating sleeve 66 of material similar to that of sleeve 55 is wound 20 or otherwise located about the heating element, and its upper end may be extended in some cases to enclose the upper enlarged tube portion 33.

The entire interior of the heating casing H 25 is preferably filled with heat-resisting or heat-insulating material 70, which may be pulverized or shredded asbestos.

Ejectors are desirably provided to facilitate the removal of objects, such as rods or 30 rivets, from the heating tubes. These comprise for each of the tubes a head 75 of metal located within the heating tube and normally resting against the bottom thereof. A stem 76 passes through suitable apertures 35 in plate 3, partition 5, and the base plate 40 of each tube, and also through an aperture in the tube base, and is secured to the head 75 in any convenient way, as by a rivet. On the outer end of each stem, in 40 position convenient for manipulation, is a knob or handle 78, or fibre or other similar or suitable material, which resists conduction of heat from the stem 76. When it is not necessary or desirable to provide means 45 for ejecting heated articles, the ejectors may, of course, be dispensed with; and especially if the heating tubes are to be used for melting metals, the bases of the tubes will be unapertured.

50 The wiring for binding screws 47 is sufficiently explained in Fig. 5, which shows the wiring compartment W in section. A common conductor or bus-bar 80, of generally rectangular form, is provided, to make contact with one of the two binding screws of each heating element. Since the heating elements are, in this particular case, arranged in three horizontal rows, as best shown in Fig. 2, two side stretches 81 and 82 of the bus-bar are arranged to make contact with the outward, or upwardly and downwardly located, terminals or binding screws 47 of the upper and lower rows of heating elements. The main portions of the stretches 55 or strips 81 and 82 are arranged to lie close

to the partition 5, and at suitable intervals the strips are bent to form upwardly extending portions or loops 84 (see Fig. 9) which are apertured to surround the binding screws. Nuts 86 are placed on the screws 70 under the bus-bar members, to firmly lock them in position and in electrical contact with the screws. The bus-bar portion 82 is also provided with extensions 88 properly arranged and bent to engage with one of the binding screws 47 of each of the central row of heating elements, and the bus-bar extension ends are locked to these binding screws by nuts, in a similar manner to the arrangement just described. 80

Individual wires 90, 91 and 92, suitably protected by thick insulation 93, are provided for each of the other binding screws of each heating element, and the ends of these wires are secured to screws by nuts, 85 in an obvious way. All of the wires 90, 91 and 92 pass through apertures in plate 4, angle bar 9 and insulating strip 17 into the wiring or switch connection box X, 90 Figs. 3 and 4. From the bus bar 80 a conductor 95, secured to the bus bar by a screw and nuts in an obvious way, and also provided with heavy insulation 96, passes through the walls and members above mentioned in connection with individual wires 90, 91 and 92, into compartment X, where the end of the conductor 95 is secured to a binding screw 97, which passes through end wall 24 and is insulated from it by a bushing 98. The inner portion of the binding screw is located in box X, and the wire 95 is secured to it by nuts 99. The outer portion of the binding screw is located in a small contact box (or main-terminal box) 100, detachably secured to the end wall 24. 100

Binding screw 97 is one of the main terminals of the heating appliance, and is adapted for connection to one of the two main or outside conductors which are led into the box 100. The other main terminal 110 of the appliance is a binding screw 102 similarly arranged and located. From the inward portion of this binding screw a wire 103 leads to a bus bar 104. 115

From bus bar 104, wires 105, 106 and 107, each go to one terminal or binding post of one of the series of switches S, which may be standard snap switches having "on" and "off" positions, and which are secured to cover plate 20. The other terminal or binding post of each switch is connected to one of the wires 90, 91 or 92 previously mentioned, so that the circuit of any heating element is completed (when the knob of its corresponding snap switch is properly positioned) by the internal switch contacts and two corresponding wires, such as 90—105, 91—106 or 92—107. The switches, as best shown in Fig. 6, are arranged in rows 120 corresponding to the arrangement of the 125 130

heating tubes, and the switches and tubes may be correspondingly numbered or otherwise identified for the convenience of the operator. Thus, the switches as shown in Fig. 6 are numbered 1 to 14, and the heating tubes are identified by similar numbers applied to the cover plate or wall 2, adjacent to the apertures 31.

The tilted or inclined arrangement of the complete appliance, previously referred to, and well shown in Figs. 1, 2 and 3, is very important and desirable because it provides for the positioning of the heating tubes so that rivets or other articles may be quickly and easily inserted in them and will then remain in position by gravity with the heads or outer ends of the rivets or rods, in a position convenient for inspection through the apertures 31. The appliance is also elevated sufficiently so that the ejector knobs 78 may be easily grasped and moved to eject the heated articles, which, when partly projecting from the apertures 31, are in position for convenient grasping with tongs. The switches S are also conveniently presented in an upward and accessible position for control of the individual heating unit circuits.

In the diagrammatic Fig. 8, the internal wiring and switches are properly identified. This figure also shows a suitable external power source and transformer with suitable external wiring for one particular arrangement. An alternator 120 (which might otherwise be a direct current generator) has main wires 121 and 122 leading through fuses 123 to a double-pole switch 124. The switch terminal wires are in circuit with the primary 125 of a suitable transformer. The transformer secondary 126 is divided into sections, with wires leading to contact points 127, 128, etc., of a suitable controller 132. From the movable contact of the controller a wire 133 is connected to binding post 102, and from one end of the secondary 126 a wire 132 goes to the binding post 97 previously mentioned.

The type of core construction of the transformer can be varied as desired, or as may be required, for the type of alternator or generator employed. When a transformer is used it can be adjusted in an obvious way, depending on the service desired of the heater, or depending on the nature of the resistance elements. For use with a direct current generator, any known or suitable rheostat or regulator may be employed. It may, of course, be necessary to adjust the rheostat or controller 132 in accordance with the number of heating elements which are in circuit at any time.

Fig. 7 shows certain modifications. The heating tube 32^a is somewhat shorter and of larger diameter than in Fig. 3, being designed particularly to accommodate a solder-

ing copper C of considerable diameter and relatively short. While for use in heating soldering coppers, having handles, no ejector would be necessary, the heating tube may be, of course, used for large and short rivets or other cylindrical objects, and an ejector is therefore shown, which may be used when desired. The heating tube in this example is so short that it does not reach nearly to the partition 5. The base plates 40 used in the previous example are therefore modified so that they consist of angle strips 40^a having portions resting against the bases of the heating tubes and having other portions or ears 40^b located near partition 5 and secured to the binding posts 47, as in the previous example.

I claim:—

1. An electric heater comprising a metal heating tube, insulation thereon, a resistance wire wound about the insulation, circuit connections for the wire, and an ejector comprising a head within the tube and normally located at the tube bottom, a stem passing through the tube bottom, and a handle accessible for operation of the ejector. 85

2. An electric heater comprising a metal heating tube, insulation thereon, a resistance wire wound about the insulation, circuit connections for the wire, and an ejector comprising a head within the tube and normally located at the tube bottom, a stem passing through the tube bottom and secured to the head, and a handle of heat-insulating material on the outward end of the stem and accessible for operation of the ejector. 95

3. An electric heating appliance comprising a heating casing, a plurality of metal heating tubes of different diameters therein, a resistance wire located about each tube, 105 and circuit connections for the wire.

4. An electric heating appliance comprising a heating casing, a plurality of metal heating tubes of different sizes therein, a resistance wire located about each tube, individual circuits for the wires, and a switch in each of said circuits to control the application of current to the wire from an outside source of energy. 110

5. An electric heating appliance comprising a heating casing, a plurality of metal heating tubes of different diameters therein, a resistance wire located about each tube, individual circuits for the wires, and a switch in each of said circuits to control the application of current to the wire from an outside source of energy. 115

6. An electric heating appliance, comprising a heating casing, a plurality of metal heating tubes therein, a resistance wire located about each tube, a terminal casing adjacent the heating casing, binding posts having portions located in each of the casings, connections between the different binding posts and ends of the different resistance 125 130

- wires, and circuit connections to the binding posts located in said terminal casing.
7. An electric heating appliance, comprising a heating casing, a plurality of metal heating tubes of different sizes therein, a resistance wire located about each tube, a terminal casing adjacent the heating casing, binding posts having portions located in each of the casings, connections between the different binding posts and ends of the different resistance wires, and circuit connections to the binding posts located in said terminal casing.
8. An electric heating appliance, comprising a heating casing, a plurality of metal heating tubes of different diameters therein, a resistance wire located about each tube, a terminal casing adjacent the heating casing, binding posts having portions located in each of the casings, connections between the different binding posts and ends of the different resistance wires, and circuit connections to the binding posts located in said terminal casing.
9. An electric heating appliance, comprising a heating casing, a plurality of metal heating tubes therein, resistance wire located about each tube, a terminal casing adjacent the heating casing, binding posts having portions located in each of the casings, connections between the different binding posts and ends of the different resistance wires, circuit connections to the binding posts located in said terminal casing, said circuit connections including a bus bar common to one binding post of each of the resistance wires, and separate conductors for the other binding posts of the resistance wires.
10. An electric heating appliance, comprising a heating casing, a plurality of metal heating tubes therein, a resistance wire located about each tube, a terminal casing adjacent the heating casing, binding posts having portions located in each of the casings, connections between the different binding posts and ends of the different resistance wires, circuit connections to the binding posts located in said terminal casing, a connection casing adjacent the binding casing, switches thereon corresponding to the individual heating tubes, and circuit connections in the last named casing connecting the individual switches with the individual binding post wires, and with a common conductor to provide for outside electrical connection.
11. An electric heater comprising a heating casing, a terminal casing at one side thereof, a switch connection casing at another adjacent side thereof, switches mounted exteriorly on the switch connection casing, a plurality of heating tubes in the heating casing, a resistance wire for each heating tube, and connections leading through the terminal casing to the switch connection casing to provide for connection of individual resistance wires to an outside source of electrical energy.
12. An electric heater comprising a heating casing, a terminal casing at one side thereof, a switch connection casing at another adjacent side thereof, switches mounted exteriorly on the switch connection casing, a plurality of heating tubes in the heating casing, a resistance wire for each heating tube, connection leading through the terminal casing to the switch connection casing to provide for connection of individual resistance wires to an outside source of electrical energy, and an ejector for each heating tube comprising a head within the tube, a stem passing through the tube bottom, and a handle on the stem located outside the terminal casing.
13. An electric heating appliance, comprising a casing of generally rectangular form, including a plurality of heating tubes, heating elements therefor, one side of the casing having openings registering with the tubes, individual switches in circuit with individual heating elements and located on an accessible wall of the casing, and ejectors having handles accessibly located adjacent another wall of the casing.
14. An electric heating appliance, comprising a casing of generally rectangular form, including a plurality of heating tubes, heating elements therefor, one side of the casing having openings registering with the tubes, individual switches in circuit with individual heating elements and located on an accessible wall of the casing, and ejectors having handles accessibly located adjacent another wall of the casing, and supporting means for the casing arranged to support it with its walls in inclined positions and with the apertures, switches and ejector handles located conveniently for access or manipulation.
15. An electric heating appliance, comprising a heating casing, a plurality of individual heating tubes therein, a wall of the casing being apertured to give access to the tubes, insulation for the tubes, a heating element for each tube, circuit connections for the heating elements, a heat-insulating filler in the casing substantially surrounding the tubes, and partitions of insulating material adjacent upper and lower sides of the casing.
16. An electric heating appliance, comprising a heating casing, a plurality of individual heating tubes of different sizes therein, a wall of the casing being apertured to give access to the tubes, insulation for the tubes, a heating element for each tube, circuit connections for the heating elements, a heat-insulating filler in the casing substantially surrounding the tubes, and par-

titions of insulating material adjacent upper and lower sides of the casing.

17. An electric heating appliance, comprising a heating casing, a plurality of individual heating tubes of different diameters therein, a wall of the casing being apertured to give access to the tubes, insulation for the tubes, a heating element for each tube, circuit connections for the heating elements, a heat-insulating filler in the casing substantially surrounding the tubes, and partitions of insulating material adjacent upper and lower sides of the casing.

18. An electric heating appliance, comprising a heating casing, a plurality of individual heating tubes therein, a wall of the casing being apertured to give access to the tubes, insulation for the tubes, a heating element for each tube, circuit connections for the heating elements, a heat-insulating filler in the casing substantially surrounding the tubes, partitions of insulating material adjacent upper and lower sides of the casing, a heating-element-terminal casing at one side of the heating casing adjacent one of the insulating partitions thereof, and conducting members extending through said partition and having electrical connections to the heating elements within the heating casing and having conductor connections within the terminal casing, one of said connections being a bus bar serving a plurality of said conducting members, a switch terminal casing at another adjacent side of the heating casing, a plurality of switches exteriorly mounted on the switch terminal casing, insulating strips in the switch terminal casing, a bus bar on one of the strips, connections from the bus bar to the switches, and individual connections from one terminal of each heating element to one terminal of the corresponding switch.

19. An electric heating appliance, comprising a heating casing, a plurality of individual heating tubes therein, a wall of the casing being apertured to give access to the tubes, insulation for the tubes, a heating element for each tube, circuit connections for the heating elements, a heat-insulating filler in the casing substantially surrounding the tubes, partitions of insulating material adjacent upper and lower sides of the casing, a switch terminal casing at one side of the heating casing, a plurality of switches exteriorly mounted on the switch terminal casing, insulating strips in the switch terminal casing, a bus bar on one of the strips, connections from the bus bar to the switches, and individual connections from one terminal of each heating element to one terminal of the corresponding switch.

20. An electric heating appliance, comprising a heating casing, a plurality of individual heating tubes therein, a wall of the casing being apertured to give access to the tubes, insulation for the tubes, a heating element for each tube, circuit connections for the heating elements, a heat-insulating filler in the casing substantially surrounding the tubes, partitions of insulating material adjacent upper and lower sides of the casing, a heating-element-terminal casing at one side of the heating casing adjacent one of the insulating partitions thereof, conducting

members extending through said partition and having electric connections to the heating elements within the heating casing and having conductor connections within the terminal casing, one of said connections being a bus bar serving a plurality of said conducting members, a switch terminal casing at another adjacent side of the heating casing, a plurality of switches exteriorly mounted on the switch terminal casing, insulating strips in the switch terminal casing, a bus bar on one of the strips, connections from the bus bar to the switches, and individual connections from one terminal of each heating element to one terminal of the corresponding switch.

21. An electric heating appliance, comprising a heating casing, a plurality of individual heating tubes therein, a wall of the casing being apertured to give access to the tubes, insulation for the tubes, a heating element for each tube, circuit connections for the heating elements, a heat-insulating filler in the casing substantially surrounding the tubes, partitions of insulating material adjacent upper and lower sides of the casing, a switch terminal casing at one side of the heating casing, a plurality of switches exteriorly mounted on the switch terminal casing, insulating strips in the switch terminal casing, a bus bar on one of the strips, connections from the bus bar to the switches, individual connections from one terminal of each heating element to one terminal of the corresponding switch, a detachable outside-connection casing and contact members therein, extending into the switch terminal casing and providing for electrical connection of outside conductors to the heating elements through the switches.

22. An electric heating appliance, comprising a heating casing, a plurality of individual heating tubes therein, a wall of the casing being apertured to give access to the tubes, insulation for the tubes, a heating element for each tube, circuit connections for the heating elements, a heat-insulating filler in the casing substantially surrounding the tubes, partitions of insulating material adjacent upper and lower sides of the casing, a heating-element-terminal casing at one side of the heating casing adjacent one of the insulating partitions thereof, conducting members extending through said partition and having electric connections to the heating elements within the heating casing and having conductor connections within the terminal casing, one of said connections being a bus bar serving a plurality of said conducting members, a switch terminal casing at another adjacent side of the heating casing, a plurality of switches exteriorly mounted on the switch terminal casing, insulating strips in the switch terminal casing, a bus bar on one of the strips, con-

nections from the bus bar to the switches, individual connections from one terminal of each heating element to one terminal of the corresponding switch, a detachable out-
5 side-connection casing and contact member therein, extending into the switch terminal casing and providing for electrical connec-

tion of outside conductors to the heating elements through the switches.

Signed at New Orleans, in the parish of ¹⁰ Orleans and State of Louisiana, this 6th day of May, A. D. 1924.

MANUEL D. DOMINGUEZ.
